UNITED STATES PATENT OFFICE.

WILLIAM BRADLEY FREAR, OF TROY, NEW YORK.

DESIGN FOR A TUG-STOP.

SPECIFICATION forming part of Design No. 34,825, dated July 23, 1901.

Application filed June 15, 1901. Serial No. 64,760. Term of patent 7 years.

To all whom it may concern:

Be it known that I, WILLIAM BRADLEY FREAR, a citizen of the United States, residing at Troy, in the county of Rensselaer and State of New York, have invented and produced a new and original Design for Tug-Stops, of which the following is a specification, reference being had to the accompanying drawings, forming part thereof.

10 Figure 1 of the drawings is a view in perspective of a tug-stop embodying my new design. Fig. 2 is a cross-section of the same taken on the broken line 2 2 in Fig. 1.

As shown in the drawings, the leading or 15 material feature of my design consists in the general T form of the stop having a gutter 1 extending longitudinally of the upper side of

the head and intersected by an aperture 2 in each lateral branch 3 of the head and having on one side of the stem 4 at its junction with 20 the head a right angle 5 and on the other side an obtuse angle 6, as shown.

What I claim as new, and desire to secure by Letters Patent, is—

The design for a tug-stop as herein shown 25 and described.

In testimony whereof I have signed my name to this specification in the presence of two subscribing witnesses.

WILLIAM BRADLEY FREAR.
